(57) **CLAIM**

The ornamental design for a lamp for a vehicle as shown and described.

DESCRIPTION

FIG. 1 is a front view of a lamp for a vehicle of the present invention;

FIG. 2 is a back view thereof;

FIG. 3 is a top plan view thereof;

FIG. 4 is a bottom view thereof;

FIG. 5 is a right side view thereof;

FIG. 6 is a left side view thereof;

FIG. 7 is a front perspective view thereof;

FIG. 8 is a back perspective view thereof;

FIG. 9 is a sectional view with internal mechanism omitted thereof, taken along the line 9-9 of FIG. 1; and,

FIG. 10 is a perspective view thereof in use, wherein the lamp for a vehicle is attached to a forklift truck and the lamp for a vehicle illuminates light so as to show lines on a floor. The broken line showing of the forklift truck and light in FIG. 10 depicts environmental subject matter and forms no part of the claimed design. All other broken lines show portions of a lamp for a vehicle that form no part of the claimed design.

The broken lines having alternating long and short segments define bounds of the claimed design and form no part thereof.
